COMBINED CIGARETTE PACKAGE HOLDER,
MAGNIFYING GLASS, AND TELESCOPE OR SIMILAR ARTICLE

Stanley Rachel, Huntington Park, Calif.

Application March 10, 1952, Serial No. 18,836

Term of patent 7 years

(Cl. D85—2)

To all whom it may concern:

Be it known that I, Stanley Rachel, a citizen of the United States, residing at Huntington Park, county of Los Angeles, and State of California, have invented a new, original, and ornamental Design for a Combined Cigarette Package Holder, Magnifying Glass, and Telescope or Similar Article, of which the following is a specification, reference being had to the accompanying drawing, forming a part hereof:

Fig. 1 is a front elevational view of a combined cigarette package holder, magnifying glass, and telescope or similar article showing my new design;

Fig. 2 is a top plan view thereof;

Fig. 3 is a side elevational view thereof, and

Fig. 4 is a bottom plan view thereof, with the top removed.

The lenses in the top and bottom of the holder are lined to indicate transparency.

I claim:

The ornamental design for a combined cigarette package holder, magnifying glass, and telescope or similar article, as shown and described.

STANLEY RACHEL.
